UNITED STATES PATENT OFFICE.

FREDERIK CHRISTIAN VIGGO ARP AND SØREN CARL JENSEN, OF COPENHAGEN, DENMARK.

STAND FOR CYCLES.

SPECIFICATION forming part of Letters Patent No. 690,221, dated December 31, 1901.

Application filed June 20, 1901. Serial No. 65,290. (No model.)

To all whom it may concern:

Be it known that we, FREDERIK CHRISTIAN VIGGO ARP, watchmaker, of Blegdamsvej 8, and SØREN CARL JENSEN, watchmaker, of 5 Nordvestvej 12, Copenhagen, in the Kingdom of Denmark, have invented certain new and useful Improvements in or Relating to Stands for Cycles, (for which we have applied for 10 patents in Denmark on the 23d of May, 1901, No. 673, and in England on the 29th of May, 1901, No. 11,084,) of which the following is a specification.

This invention relates to stands for cycles, and has for its object to provide an improved 15 cycle-stand hinged to the front fork of the cycle-frame and adapted to be brought down forward of the front wheel, so as to support the cycle when desired, and thus enable the latter to be placed in an upright position, 20 while when the machine is to be ridden the stand is folded alongside the front fork.

Referring to the accompanying drawings, Figure 1 shows a side elevation of the front portion of a cycle provided with our improved 25 device, the stand being shown in its operative position. Fig. 2 shows the same when not in use. Fig. 3 is a front elevation corresponding to Fig. 1. Fig. 4 shows means for locking the stand in its operative position.

To each leg of the front fork *a* is fixed an angle-plate *b*, firmly retained in position by 30 a strap *c*, surrounding the fork. The front axle *d* passes through a hole in the said plates, so that the latter cannot become displaced.

To the ends of the upwardly-directed arm *e* of the plate *b* are pivoted bars *f* of a length 35 slightly in excess of the radius of the cycle-wheel *g*. Upon both the bars *f* is fitted a longitudinally-moving slide *h*, carrying a cen-

trally-disposed shoe or drag, of caoutchouc or the like, upon which the front wheel of the machine rests when the stand is turned down. To the lower extremity of the bars *f* are hinged 40 laterally-projecting bars or feet *i*, which in the

idle position, Fig. 2, of the stand are brought 45 close against the sides of the bars *f*, while in the operative position they project sidewise at right angles therewith, Fig. 3, so as to afford a solid support to the cycle. The amount

50 of sliding movement of the slide *h* upon the bars *f* is limited, so as to be at a distance from

the wheel-rim when the stand is turned upward and not act as a brake. When the stand is turned down, the slide *h* comes into contact with the wheel-tire simply because the 55 pivot-point is above the axle of the wheel, and therefore the slide is pressed outward against the ends of the bars *f*. At the same time the feet *i* are turned sidewise into the position shown at Fig. 3, where they are locked 60 by a bolt caused to engage in a notch in the foot by the downwardly-moving slide *h*. When the slide has entered its lowermost position, the stand is fully extended, and so forms a firm support for the front wheel of the 65 cycle. In this position the stand and the cycle can be locked by any convenient arrangement. For example, one of the bars *f*, Fig. 1, may be provided with an arm *k*, which latter when the stand is lowered into its working 70 position is disposed parallel with one leg of the front fork and is then locked by means of the ordinary cycle-locking device *l*. A more convenient locking device is shown in Fig. 4. To one of the legs *f* of the fork is 75 pivoted a pawl *m*, adapted to engage in a bow-piece *n* or the like, integral with the plate *b*, in such a manner as to retain the stand in its operative position, the pawl being suitably locked on the bow-piece. 80

When raising the stand, the slide *h* moves automatically back upon the bars *f*, thereby disengaging the feet *i* and causing them to move flat against the sides of the said bars *f*. Means, such as a lock or pawl, are provided 85 for retaining and locking the stand in its inoperative position and preventing it falling down during the riding of the cycle.

The stand need not be permanently attached to the cycle, and the plates *b* may be 90 so arranged as to enable them to be readily secured to the fork *f* when required for use and to be securely held in position thereon.

We claim—

A folding cycle stand or support adapted 95 to be secured to the cycle, and consisting of two pivoted bars disposed alongside the front fork and provided with a longitudinally-movable shoe or slide, so arranged as to engage with the wheel-tire when the stand is lowered, 100 and of two legs pivoted to the ends of the bars, which legs in the raised position of the

stand are disposed alongside the outside of the bars, but in its lowered position project sidewise at right angles to the stand and the cycle so as to firmly support the latter in its 5 upright position; means being provided for locking the stand both in its lowered and raised positions.

In witness whereof we have hereunto set our hands in presence of two witnesses.

FREDERIK CHRISTIAN VIGGO ARP.
SØREN CARL JENSEN.
